Inv'tor:

UNITED STATES PATENT OFFICE.

OLIVER I. HESS, OF SCOTTDALE, PENNSYLVANIA.

OIL-CAN.

SPECIFICATION forming part of Letters Patent No. 417,639, dated December 17, 1889.

Application filed June 28, 1889. Serial No. 315,852. (No model.)

To all whom it may concern:

Be it known that I, OLIVER I. HESS, a citizen of the United States, residing at Scottdale, in the county of Westmoreland and State 5 of Pennsylvania, have invented a new and useful Oil Can or Stand, of which the following is a specification.

This invention has relation to oil cans or stands; and among the objects in view are to 10 provide the same with an automatic alarm, whereby the alarm will be sounded when the time for cutting off the supply arrives.

The invention consists in a can the upper 15 end of which is provided with an air-tight stopper threaded thereon, a spout projecting from the can and provided with a surrounding air-tube, an air-nipple projecting from the can above the spout, and an elastic sleeve loosely connecting the nipple and air-tube, 20 whereby, in the act of pouring or emitting the contents of the can through the spout, air will be drawn through the air-tube, the elastic coupling, and nipple into the can, to fill the 25 vacuum caused by the egress of oil, and thus sound the alarm, which, in the present instance, is formed of a piece of flexible flabby elastic tubing.

Referring to the drawings, Figure 1 represents a perspective of an oil can or stand constructed in accordance with my invention. Fig. 2 is a vertical longitudinal section, enlarged, of the upper portion of the can or stand; Fig. 3, a detail in section of the acoustic alarm.

Like numerals of reference indicate like parts in all the figures of the drawings.

1 represents an ordinary oil-can of any shape desired, at the upper end of which there is mounted a screw-threaded stopper 2, and 40 an interposed rubber washer 3. The upper portion of the can is preferably provided with a cone-shaped dome 4; but it may be otherwise formed, if desired. From the dome, at one side thereof, there projects a vertically 45 and laterally disposed eduction-spout 5, the upper portion of which is bent at an angle, as at 6, to the remainder of the spout, and is in about a horizontal line with a nipple 7, communicating with the interior of the dome and 50 projecting laterally from the apex thereof. Upon the lateral portion 6 of the spout 5 there is mounted over the same and secured

thereto an inverted-U-shaped air-tube 8, the front end of which terminates flush with the end of the spout, said tube projecting slightly 55 beyond the lateral portion 6 at the rear of the spout and terminating in a nipple 9 in a horizontal line with the nipple 7.

10 represents a coupling, which in this instance forms the acoustic alarm, and the 60 same is formed of a sleeve made of very light thin rubber, the ends 11 of which are connected with the nipples 7 and 9, and intermediate said ends the walls of the rubber 65 fold upon themselves or lie flat.

The operation of my invention is as follows: To fill a lamp or other receptacle for oil, the bent portion 6 of the spout 5 is introduced into the oil-receiving opening of the vessel and the oil permitted to flow from the can 1 70 therein. The proportion of the bent portion 6 is such that the end thereof, when introduced into an oil-receptacle, will be a short distance below the mouth of the receptacle and at about a height which is desired the oil 75 should rise to. As the oil passes in a vacuum is formed in the can 1, and the air is drawn in through the air-tube 8, coupling 10, and nipple 7 to take the place of the escaping oil. In so doing the walls of the sleeve 10 lying together are forced apart, and a horn-sounding 80 noise is made, which continues until the oil rises even with and closes the air-tube 8, thereby arresting the flow of oil and stopping the sound, when it will be apparent that the 85 vessel is filled, and thus any likelihood of overrunning the vessel is avoided.

By locating the alarm upon the outside of the can I obviate any liability of said alarm becoming oil-clogged, and thereby rendering 90 the same inoperative. Furthermore, a clearer and more distinct alarm is given, which is of importance should it be necessary to emit the oil in a fine stream.

By reason of the walls of the coupling 10 95 folding one upon the other when the can is at rest I efficiently cut off the interior of the can from the outer atmosphere, and in this manner prevent the escape of disagreeable odors through the air-passages.

A further advantage of the flexible flabby coupling is that in tilting the can, as is often the case when filling small vessels, the said coupling can be compressed by the thumb

and finger of the operator, so as to prevent admission of air and any consequent premature emission of oil.

Having described my invention, what I claim is—

1. An oil-can provided with a spout, an air-tube mounted on the spout and terminating in a nipple, and an air-tube mounted on the can and connected with the nipple by an acoustic alarm, substantially as specified.
2. An oil-can provided with a spout provided with an air-tube terminating at its rear end in a nipple, a nipple projecting from the can, and a flabby flexible coupling, as 10, connecting the nipples, the walls of the coupling intermediate the nipples being designed to normally close one upon the other, substantially as specified.
3. An oil-can provided with a spout, the upper portion of which is bent at an angle to the main portion, an inverted-U-shaped air-tube mounted on the bent portion and mounted on its front end flush therewith and having its rear end extended beyond the bent

portion to form a nipple, and a nipple projecting from the upper end of the can in line with the air-tube, and the rubber coupling 10, connecting the nipples, the walls of which normally lie one upon the other, substantially as specified.

4. A can provided with an air-tight stopper screwed thereon, a spout projecting from the can and provided with a surrounding air-tube, an air-nipple projecting from the can above the spout, and an elastic sleeve loosely connecting the nipple and air-tube, whereby in the act of pouring the contents of the can through the spout air will be drawn through the air-tube, the elastic coupling, and nipple into the can to fill the vacuum caused by oil, and thus sound an alarm, as set forth.

In testimony that I claim the foregoing as my own I have hereto affixed my signature in presence of two witnesses.

OLIVER I. HESS.

Witnesses: E. M. HUSBAND, S. K. EBERSOLE.
